PUMP FOR EVAPORATING SYSTEMS

Philip B. Sadtler, Birmingham, Ala., assignor to
 Goslin-Birmingham Manufacturing Company,
 Inc., a corporation of Alabama

Application September 3, 1940, Serial No. 355,125

1 Claim. (Cl. 103—41)

My invention relates to an evaporating system embodying a plurality of effects with transfer pumps for pumping the liquor being evaporated from one effect to another and has for an object the provision of means in apparatus of the character designated by which a predetermined minimum head is maintained in the intake sides of the pumps.

A more specific object of my invention is to provide, in an evaporating system, a bypass connection from the discharge to the intake side of a transfer pump, and float control means in communication with the intake side to vary communication through the bypass.

In multiple effect evaporating systems, there is usually associated with each effect a transfer pump adapted to pump the liquor discharged from that effect to another effect, usually the next preceding effect. In order to control the flow from the pump, it has heretofore been the practice to interpose a valve in the discharge line from the pump whereby the discharge may be restricted and such load thereby imposed upon the pump as to slow down the discharge. Such an arrangement does not prevent cavitation, and does impose an additional load on the pump, consuming an undue amount of power and involving unnecessary wear on the pump, due to the additional frictional load.

I have discovered that cavitation may be prevented with a much less expenditure of power and much more satisfactory performance of the pump, by leaving the discharge conduit wide open and by providing a bypass between the discharge conduit and intake conduit of the pump, with float controlled valve means in the bypass operable by the liquor in the intake conduit to control the flow of liquor through the bypass. By this means, I impose a predetermined minimum head on the intake side of the pump which prevents cavitation, while the unrestricted discharge from the pump permits it to run freely without consuming excessive power and without excessive wear.

Apparatus embodying features of my invention is illustrated in the accompanying drawing forming a part of this application, in which

Fig. 1 is an elevation showing my invention applied to two effects of a multiple effect system, omitting details of construction not necessary to an understanding of my invention;

Fig. 2 is a detail sectional view showing a float controlled valve mechanism adapted for use with my invention; and

Fig. 3 is a diagrammatic view of a multiple effect evaporating system embodying my invention.

Referring to the drawing, I show in Fig. 1 two effects 10 and 11 of a multiple effect system. 5 Steam is admitted into the calandria of the effect 10 through a steam conduit 12, and vapor from the effect 10 passes through a conduit 13 to the calandria of the effect 11, as is well understood. Liquor being evaporated passes in series through 10 the effects, being initially admitted to the effect 11 through a conduit 14. Connected to the upper end of each of the effects 10 and 11 is a conduit 16 leading to the intake side of a transfer pump 17 associated with each of the effects and located 15 preferably at a lower level than its associated effect. The pump 17 is driven by a motor 18 and discharges the liquor through a discharge conduit 19 leading to the next preceding effect, in the direction of steam flow. Inasmuch as there 20 is a higher vapor pressure in the next preceding effect, the transfer pump is discharging liquor against a higher head than that on the intake side of the pump. Connecting the intake conduit 16 and discharge conduit 19 is a bypass conduit 25 21, in which is located a valve 22 controlling the flow of liquor through the bypass.

The valve 22 is operated by float control means comprising a float member 23 located in a chamber 24 which is connected to the intake conduit 20 16, by means of branch conduits 26 and 27. The float member 23 is secured to a rod 25, which is pivoted at 28 in the chamber 24 and is connected by means of a link 29 with the valve 22, as shown in Fig. 2. It will be seen that when the liquor in 35 the intake conduit 16 is above the level of the float 23 and chamber 24, the float 23 moves upwardly, closing the valve 22, and all the liquor discharged by the transfer pump 17 passes through the conduit 19 to the next succeeding 40 effect.

Should the liquor level fall below the chamber 24, the float 23 falls, opening the valve 22 and permitting the liquor being discharged through the discharge conduit 19 to flow through the bypass conduit 21 into the intake conduit 16.

Due to the higher vapor pressure in the effect into which each pump is discharging as compared with the pressure in the effect from which it is receiving liquor, the minimum head indicated 59 on the drawing is lower than the head against which the pump 17 normally operates. Accordingly when the bypass valve 22 opens, there is insured a flow of liquor through the bypass 21 into the intake conduit 16, and the valve 22 55 functions to restrict that flow as the level rises

in the chamber 24. Cavitation is thus prevented and a full, free discharge from the pump is provided.

Referring to Fig. 3 of the drawing, there are shown diagrammatically five effects, Nos. 1, 2, 3, 4 and 5, in which the vapor pressure decreases by gradations from No. 1 to No. 5. The initial steam is admitted to the effect 1 through conduit 31, and the succeeding effects are connected by vapor conduits 32, 33, 34 and 35 respectively, the vapor from effect No. 5 passing through a conduit 36 to a condenser, not shown. Liquor to be evaporated passes through the effects in counter flow relation to the heating medium, being introduced into effect No. 5 through a conduit 37. The liquor, therefore, in passing through the effects, is subjected to an ascending pressure gradient. The transfer pumps 17, one of which is associated with each of the effects, cause the flow of liquor from effect to effect in series, being finally discharged through a conduit 38, as shown. By interposing the float control bypass valve 22 between the discharge and the intake conduits of each of the pumps 17, a free flow of liquor is provided corresponding to the

rate of evaporation of each of the effects, with a minimum resistance to flow and with a reduction in power consumption and wear of parts as compared with evaporating systems heretofore known to me.

5 While I have shown my invention in but one form, it will be obvious to those skilled in the art that it is not so limited, but is susceptible of various changes and modifications, without departing from the spirit thereof, and I desire, therefore, that only such limitations shall be placed thereupon as are imposed by the prior art or as are specifically set forth in the appended claim.

10 15 What I claim is:

In an evaporating system, a transfer pump, intake and discharge conduits connected to the pump, a bypass connecting the discharge conduit to the intake conduit, a valve in the bypass, and 20 float control means in the intake conduit in advance of the bypass for operating the valve to vary the rate of flow through the bypass responsive to the head in said conduit.
